(57) **CLAIM**

We claim the ornamental design for a dispensing system for liquid, as shown and described.

DESCRIPTION

FIG. 1 is a front perspective view of our new design for a dispensing system for liquid;
FIG. 2 is a rear perspective view thereof;
FIG. 3 is a bottom front perspective view thereof;
FIG. 4 is a front elevation view thereof;
FIG. 5 is a rear elevation view thereof;
FIG. 6 is a left-side elevation view thereof;
FIG. 7 is a right-side elevation view thereof;
FIG. 8 is a top plan view thereof;
FIG. 9 is a bottom plan view thereof; and,
FIG. 10 is an exploded top front perspective view thereof.
The broken lines in the drawings depict portions of the dispensing system for liquid that form no part of the claimed design.

1 Claim, 7 Drawing Sheets
